To all whom it may concern:

Be it known that we, Sidney Weisberg and Herman M. Freyberg, citizens of the United States of America, and residing, respectively, at Stamford, in the county of Fairfield and State of Connecticut, and at Scarsdale, in the county of Westchester and State of New York, have invented a new, original, and ornamental Design for a Ribbon Reel, of which the following is a specification, reference being had to the accompanying drawings, forming part thereof.

In the drawings, Fig. 1 is a perspective view of a ribbon reel showing our new design. Fig. 2 is an end elevational view of the reel.

The dash and dotted lines in Fig. 1 are for illustrative purposes only and illustrate the ribbon normally wound about the reel.

The design is characterized by the relatively

We claim:
